UNITED STATES PATENT OFFICE.

EUGENE MOREHOUSE, OF PROVIDENCE, RHODE ISLAND, ASSIGNOR TO B. A. BALLOU & CO., INC., OF PROVIDENCE, RHODE ISLAND, A CORPORATION OF RHODE ISLAND.

DESIGN FOR A SAFETY CATCH FOR PIN STEMS.

Application filed May 1, 1925. Serial No. 13,278. Term of patent 14 years.

To all whom it may concern:

Be it known that I, EUGENE MOREHOUSE, a citizen of the United States, residing in the city of Providence, county of Providence, and State of Rhode Island, have invented a new, original, and ornamental Design for a Safety Catch for Pin Stems, of which the following is a specification, reference being had to the accompanying drawing, forming a part thereof.

The figure is a perspective view of a safety

catch for pin stems, showing my new design. The catch consists of spaced arms with one of said arms having an outwardly-projecting bullet-shaped portion of ornamental attractive appearance.

I claim:

The ornamental design for a safety catch for pin stems, as shown and described.

EUGENE MOREHOUSE.
